and the oil holding capacity of the engine is increased by the use of a single throw crank shaft.

UNITED STATES PATENT OFFICE

JOHN L. HENDERSON, OF BOONE GROVE, INDIANA

INTERNAL COMBUSTION ENGINE

Application filed October 1, 1930. Serial No. 485,690.

This invention relates to improvements in internal combustion engines.

The main object of the invention is to provide an engine in each cylinder of which a pair of opposed pistons are mounted and adapted to be forced outward by an explosion of fuel occurring between the pistons.

Another object is to provide an engine of the character described in which the pistons are operatively connected by bell crank levers and connecting rods to a crank shaft arranged parallel with the axes of the cylinders, whereby any desired number of cylinders may be mounted radially around the crankshaft to drive the same thus making the engine particularly adapted for use on aircraft.

A further object is to provide an engine of the character described in a simple and efficient form.

The foregoing and other objects together with means whereby the same may be carried into effect will best be understood from the following description of a preferred embodiment of the invention taken in connection with the accompanying drawings wherein:

Figure 1 is an end view of my improved engine constructed with three cylinders, the end of the crankcase being shown open.

Figure 2 is an enlarged vertical cross section through the upper cylinder and the crankcase shown in Figure 1.

Figure 3 is an enlarged end elevation of the master connecting rod and associated link connecting rods.

Figure 4 is an enlarged detail plan view, partially in section, of the connecting means between the bell crank levers and connecting rods.

Figure 5 is an enlarged detail cross section through one of the poppet valves.

Figure 6 is an enlarged detail cross section through one of the valve tappet guides and rollers.

Referring now more particularly to the drawings the reference numeral 1 designates the crankcase of substantially cylindrical form and through which the single throw crank shaft 2 is journaled in the bearings 3.

The crank 4 of the crankshaft 1 is disposed centrally of the length of the crankcase 1 and an opening 5 is provided through the wall of the crankcase in alignment with each of the cylinders 6, which are here shown and described as being three in number and equally spaced around the crankshaft. Each cylinder is elongated in form and is supported adjacent its ends by spaced ribs or spokes 7 and 8 radially extended from each end of the crankcase 1. A pair of pistons 9 and 10 are slidably mounted in each of the cylinders 6, with their heads or end faces turned inwardly and the usual piston rods 11 and 12 of these pistons are passed outward through the opposite open ends 13 of the cylinders 6. Bell crank levers 14 and 15 are provided and the same are fulcrumed at 16 between spaced bearing ears 17 extended outward from the ribs 7 and 8 at some distance inward from the cylinders 6. These bell crank levers 14 and 15 have their long arms 18 extended outward from the center of the engine and pivotally connected at 19 to the outer ends of the piston rods 11 and 12 and have their relatively shorter arms 20 extended inward toward each other through elongated slots 21 in the ribs 7 and 8 which allow rocking movement of the levers as will be understood, the said arms 20 being of such length that they terminate short of meeting at their inner ends as shown in Figure 2. These inner ends of the short arms 20 are bifurcated at 22 (Figure 4) and bearing blocks 23 and 24 are pivoted in the ends of these short arms of the bell crank levers by means of the oppositely extended studs 25 on the blocks which are journaled in the sides 26 formed by the bifurcation of the arms 20. The bearing blocks 23 and 24 are provided with bores 27 extended at right angles to the studs 25 and on a common axial plane therewith. Slide rods 28 are rotatably and slidably mounted through the bores 27 of each adjacent pair of bearing blocks 23 and 25 in each set of bell crank levers 14 and 15 and these rods are diametrically enlarged at a point intermediate their ends as shown at 29. A master connecting rod 30 has its bearing 31 journaled on the crank 4 of the crankshaft 2 and two link rods 32 and 33 are

pivoted by their inner ends at 34 to this bearing, the said bearing 31 being formed of two sections 35 and 36 joined together by bolts 37 in the usual manner. The outer ends of the 5 master connecting rod 30 and the link rods 32 and 33 are provided with apertures 38 in which are mounted the enlarged central portions 29 of the slide rods 28, the bell crank levers 14 and 15 being thus connected to the 10 crankshaft 2 through the connecting rod assembly.

Referring to Figure 1 of the drawings, the 15 pistons 9 and 10 are shown in their innermost position or in the position at which the mixture is fired between them. Upon the explosion of the fuel between the pistons they will be forced outwardly in the cylinder 6 causing the longer arms 18 of the bell crank levers 14 and 15 to swing outward from the ends of 20 the cylinder and raise the short arms 20. This action pulls upward upon the master connecting rod 30 and partially rotates the crankshaft 2, the pistons in the other cylinders 6 then acting in the same manner and in 25 the proper sequence to continue the rotation of the crankshaft in the usual manner. Upon an outward movement of the shorter arms 20 of the bell crank levers the inner bifurcated ends 22 thereof move apart as will be understood 30 and the bearing blocks 23 and 24 move outward on the slide rods 28, the latter at the same time rotating slightly in the said bearing blocks as the connecting rod assembly swings in driving the crankshaft. In order 35 to brace the short arms 20 of the bell crank levers 14 and 15 against the lateral stress brought about by the rotation of the bearing 31 of the connecting rod assembly arcuate side pieces 39 are secured on each side of the 40 said arms 20 by screws 40, the said side pieces 39 extending inwardly between the crankcase 1 and the ribs 7 and 8.

Spark plugs 41 are seated in the walls of the cylinders 6 at the longitudinal centers 45 thereof and are connected in the usual manner with the conventional timer and high tension magneto (not shown). Intake and exhaust valves 42 and 43 are provided on each cylinder 6 and the same include the housings 44 secured on the outer wall of the cylinders at each side of the spark plugs 41. Conventional poppet valves 45 are mounted in the 50 housings 44 and are spring set by coil springs 46 to normally seat in seats 47 formed at the 55 inner ends of ports 48 provided in the walls of the cylinders 6 as shown in Figure 5. Valve rocker arms 49 are fulcrumed at 50 in brackets 51, on the valve housing 44 and these 60 rocker arms engage the stems of the valves 45 in the usual manner. An intake and exhaust cam 52 is freely mounted on the crankshaft 2 and carries the gear 54, the whole turning independently of the crankshaft. A 65 pinion 55 fixed on the crankshaft 2 meshes with a gear 56 on a counter shaft 57 journaled

in the crankcase and a pinion 58 on this counter shaft 57 meshes with the gear 54 to drive the cam 52 at a fraction of the speed of the crankshaft. Tubular valve tappet guides 59 are mounted through the wall of the crankcase 1 at some distance to each side of the radii passing through the crankshaft 2 and cylinders 6 and valve tappets 60 are slidably mounted through these guides 59 and spring set by coil springs 61 to normally move inward toward the crankshaft. Valve tappet rollers 62 are journaled in the forked inner ends of the valve tappets 60 and are adapted to ride the cam 52 in the usual manner. Valve push rods 63 are pivoted by one end at 64 to the valve tappets 60 and are pivoted at their other ends to the valve rocker arms 49 as shown at 65. The arrangement is such that the intake and exhaust valves of each cylinder are opened in the proper sequence and in accordance with the usual four cycle principle. The usual intake and exhaust manifolds (not shown) are connected to the valve 75 housings 44 in the conventional manner.

From the foregoing it will be apparent 80 that I provide a simple, efficient, powerful and compactly arranged engine and while the same is here shown as embodying three cylinders it is to be understood that any other desired number or arrangement of cylinders may be used as desired. Also, while the engine is particularly adapted for use on aircraft due to its decreased head resistance relative to the usual engine of equal power, it is understood that the engine may be used 85 for other purposes as for instance on automobiles.

While I have herein set forth a certain preferred embodiment of my invention it is understood 90 that I may vary from the same in minor structural details, so as best to construct a practical device for the purposes intended, not departing from the spirit of the invention and within the scope of the appended claims.

I claim:

1. In a device of the kind described, a cylinder having open ends, a crank shaft journaled parallel with the cylinder, a pair of opposed pistons in the cylinder, piston rods extended from the pistons out through the open ends of the cylinder, bell crank levers connected at one end to the said piston rods, bearing blocks pivoted in the other ends of the bell crank levers, a slide rod slidably mounted through the said bearing blocks and a connecting rod connecting the said slide rod and crankshaft.

2. In a device of the kind described, a cylinder having open ends, a pair of opposed pistons in the cylinder, a crankshaft journaled parallel with the cylinder, bell crank levers, and means connecting the bell crank levers and the pistons and crank shaft for ro-

tation of the crankshaft by reciprocation of the pistons in the cylinder.

3. In a device of the kind described, a cylinder having open ends, a pair of opposed pistons mounted in the cylinder, a crankshaft journaled parallel with the cylinder, a connecting rod mounted on the crankshaft, a pair of bell crank levers comprising long and short arms, piston rods connecting the said pistons and the long arms of the bell crank levers, and a slideable and rotatable connection between the short arms of the bell crank levers and the connecting rod.

4. In a device of the kind described, a cylinder having open ends, a pair of opposed pistons mounted in the cylinder, a crankshaft journaled parallel with the cylinder, a connecting rod mounted on the crankshaft, a pair of bell crank levers comprising long and short arms, piston rods connecting the said pistons and the long arms of the bell crank levers, and a slideable and rotatable connection between the short arms of the bell crank levers and the connecting rod, the said slideable and rotatable connection comprising bearing blocks journaled in the ends of the said short arms of the bell crank levers, and a slide rod secured to the connecting rod and slideably and rotatably mounted in the said bearing blocks.

5. In a device of the kind described, a crankshaft, a plurality of cylinders arranged around the crankshaft and parallel therewith, a pair of pistons in each cylinder, bell crank levers arranged at each end of the cylinders, and means connecting the pistons, bell crank levers and the crankshaft for rotation of the latter by the reciprocation of the said pistons in the cylinders.

40 In testimony whereof I affix my signature.
JOHN L. HENDERSON.
